Inventor:
Irving Gnatowsky

UNITED STATES PATENT OFFICE

IRVING GNATOWSKY, OF BROOKLYN, NEW YORK

COLLAR CLASP

Application filed June 7, 1929. Serial No. 369,123.

This invention relates to new and useful improvements in clasps for collars and aims to provide a novel, simple, ornamental and inexpensive clasp of this variety wherein the ends of the clasp will properly engage with the ends of the outer fold of the collar to prevent loss of the clasp.

Furthermore the nature of the invention is such as to enable the present clasp to be easily associated with or removed from the collar which overcomes one of the main disadvantages inherent in clasps of this variety.

With the foregoing and other objects it will become apparent as the nature of the invention will be better understood from the following specification when considered in conjunction with the accompanying drawing.

In the drawing wherein like reference characters indicate corresponding parts throughout the various views.

Figure 1 is a front elevation, in dotted lines, of a conventional collar with which is associated my improved clasp,

Figure 2 is a side elevation of the improved clasp,

Figure 3 is a detailed longitudinal sectional view, and

Figure 4 is an enlarged transverse view taken substantially upon the line 4—4 of Figure 3 and looking in the direction of the arrows.

Now having particular reference to the drawing my novel clasp consists of an arcuate shaped backing strip 5 of suitable length and width and preferably of metal, bone or other desirable material.

Pivoted intermediate their ends to the convex surface of this backing strip 5 and in equally spaced relation from the opposite ends of said backing strip and in outwardly spaced relation therewith are longitudinally extending clasp levers 6—6. These levers are preferably of the same material as the material comprised in the backing strip 5 and the outer ends of these levers are turned inwardly to provide collar engaging knobs or heads 7—7 which are normally in engagement with the ends of the backing strip when the clasp is not in use.

In order to facilitate the pivotal associa-

tion of these levers 6—6 with the backing strip 5 in spaced relation with said backing strip the opposite side edges of each lever are formed with inwardly extending ears 8—8 their lower ends of which are loosely associated with a cross pin 9 suitably secured to the backing strip. However, it is to be understood that I do not desire to be limited to this particular character of pivotal association between the levers and backing strip as departures may be had therefrom without affecting the operation of the device.

The inner end of each lever 6 is formed at its opposite longitudinal edges with inwardly extending ears 10—10 the opposite vertical edges of each of which are formed directly beneath the respective lever 6 with inwardly extending fingers 11—11. These ears 10—10 and fingers 11—11 serve to provide a housing for an expansible coil spring 12 arranged therein and between the backing strip 5 and levers 6. Obviously each coil spring serves to maintain the forward headed end of the respective lever 6 in frictional engagement with the backing strip 5 and when the clasp is in position as illustrated in Figure 1 to tightly secure the collar material between the heads of the levers and said backing strip. When it is desired to apply or remove the clasp all that it is necessary is to press with the thumb and forefinger upon the inner ends of the levers and the center of the backing strip. This then raises the forward ends of the levers away from the backing strip as is obvious.

In view of the foregoing description when considered in conjunction with the accompanying drawing it will be apparent that I have provided a novel, simple and useful collar clasp that is well adapted for all of the purposes heretofore designated and even though I have herein shown and described the invention as consisting of certain detailed structural elements it is nevertheless to be understood that some changes may be made therein without affecting the spirit and scope of the appended claim.

Having thus described the invention, what is claimed as new is:

In a collar clasp of the character described,

a backing member, a pair of levers pivoted intermediate their ends to the backing member adjacent its opposite end and extending longitudinally therewith and in spaced relation thereto, heads upon the outer ends of the levers, an expansible coil spring between the inner end of each lever and the backing member, and a spring retaining housing associated with each lever.

5 10 In testimony whereof I affix my signature.
IRVING GNATOWSKY.
